UNITED STATES PATENT OFFICE

GEORGE H. BRADY, OF BALTIMORE, MARYLAND, ASSIGNOR TO IMPROVED FIRE DETECTOR CORPORATION, OF BALTIMORE, MARYLAND

TEMPERATURE SENSITIVE ELECTRICAL CIRCUIT CLOSER

Application filed January 27, 1931. Serial No. 511,590.

This invention relates to certain new and useful improvements in temperature sensitive electrical circuit closers, and particularly circuit closers of that type in which the circuit closing action is effected by the bowing movement of a bimetallic contact strip having a contact portion movable into engagement with a pointed contact member.

In the use of such temperature sensitive circuit closers in a fire alarm system, it is the general practice to fix the circuit closing device on the ceiling or a wall support adjacent to the ceiling, so that the bimetallic circuit closing strip will be influenced by the rising heated air when a fire breaks out in the guarded room or apartment in which the circuit closer is arranged. The contact member and circuit closing strip are commonly made of certain metals which are subject to surface oxidation or corrosion interfering with a good electrical contact, and to prevent such oxidation the contact member and strip may be provided with a coating of non-oxidizable metal. It is difficult, however, to prevent corrosion in cases where the circuit closer is exposed to the action of sulphuric or nitric or other acid vapors or chlorine or other gases in the atmosphere, and it is also impossible to construct the circuit closer so that it will be absolutely proof against the coating of the contact surfaces by mist-like deposits of paints or other wall coatings dissipated into the atmosphere in paint spraying actions.

For these reasons, the Underwriters Laboratories' standards require that the stationary contact member and contact portion of the contact strip of the electric switch be so guarded or constructed as to protect the same from oxidation, corrosion or deposits of electric-insulating substances thereon, and/or that the contact elements have such an action as to ensure a good physical contact for a positive circuit closing operation when the thermostatic strip moves into engagement with its coating contact member.

In my application for patent, filed November 12, 1930, Serial No. 495,255, I have disclosed a temperature sensitive electrical circuit closer which is proof against oxidation and corrosion and which embodies novel and improved means for securing a wiping engagement of the circuit closing contacts, whereby any deposits thereon will be removed and a good electrical contact ensured. It is, however, desirable to provide a temperature sensitive electric circuit closing or switch device which will not only be proof against deleterious actions of the character referred to, but which may be employed in conjunction with a standard outlet box of wall or ceiling type, so that its binding posts or terminals may be connected to circuit conductors extending into the outlet box, and thereby enabling the circuit closer to be connected up in a circuit having concealed or surface wiring.

One object of my invention, therefore, is to provide a temperature sensitive circuit closing switch which is adapted for use in conjunction with a standard outlet box and which embodies a novel and improved construction of casing for this purpose.

A further object of the invention is to provide a circuit closer having a casing comprising a back section and a body section, which back section is adapted to be secured to the outlet box and to support the switch device so that its contacts will be located in the body section and its binding posts or terminals in the outlet box, and in which the body section is so constructed as to effectually protect the switch elements therein from injury while especially designed for the rapid passage of rising currents of heated air therethrough, so as to secure a practically instantaneous circuit closing action in the event of a conflagration.

A still further object of the invention is to provide a unitary type of switch device which may be bodily applied to and re-

5 moved from the back of the casing, and to provide a construction of casing in which one and the same style of body section may be interchangeably applied to different styles of back plates or sections.

10 With these and other objects in view, the invention consists of the features of construction, combination and arrangement of parts, hereinafter fully described and claimed, reference being had to the accompanying drawings, in which:—

Fig. 1 is a front view of a temperature sensitive circuit closer embodying my invention.

15 Fig. 2 is a front view of the back plate thereof and the switch device applied thereto.

Fig. 3 is a sectional view on line 3—3 of Fig. 4 showing the circuit closer as applied for use in connection with a standard concealed type of outlet box.

20 Fig. 4 is a section taken on line 4—4 of Fig. 3.

Fig. 5 is an inner or rear elevational view of the body section of the casing.

25 Fig. 6 is a view of a portion of the switch device, showing the contact elements in normal condition.

Fig. 7 is a similar view showing the contact elements in circuit closing contact.

30 Fig. 8 is a section on the line 8—8 of Fig. 10 showing the circuit closer as employed in conjunction with a surface type of outlet box.

Fig. 9 is a front view of the back plate of 35 the casing shown in Fig. 8.

Fig. 10 is a sectional view on the line 10—10 of Fig. 8.

Referring now more particularly to Figs. 1 to 7, inclusive, of the drawings, 1 designates the enclosing casing of the circuit closer, which may be made of cast or stamped metal and which comprises a body section 2 and a base plate or back section 3. The casing 1 here shown is of circular form and comparatively shallow and is designed to be employed in connection with a standard concealed type of outlet box 4 which fits within a concavity or depression in the wall or ceiling 5 upon the surface of which the circuit closer is applied.

55 The body section 2 of the casing comprises a front or body plate 6 having a rearwardly extending annular wall portion 7 normally open at its rear side, or that side opposite the plate 6, and adapted to fit within a receiving groove or recess 8 formed by an annular flange 9 projecting from the face of the plate 3. This plate 3 is formed with a front surface 10 extending rearwardly on an outward and rearward bevel or slope toward the wall or ceiling 5, so as to give a desired finished or ornamental conformation thereto. The plate 3 is of sufficiently greater diameter than the box 4 to cover the outer open side thereof and to lap over the adjacent

70 portions of the wall or ceiling 5. In the rear face of the plate 3 is a recess 11 to receive the edge of the box 4 at its open side, whereby the front of the outlet box is effectually closed and concealed by the circuit closer when the latter is applied for use. Any suitable means, such as screws 12, may be employed to detachably secure the casing members 2 and 3 to lugs 12' on the box 4. A casing structure is thus provided which 75 comprises a front wall 6, an intermediate wall 7, and a removable rear wall formed by the back plate 3, which serves as a cover.

80 The wall 7 of the body section 2 is formed with an annular series of rectangularly-shaped spaced slots or openings 13, preferably formed by making such wall of an annular series of rectangular or oblong rectangular bars 13', providing a grating-like form of perforate wall. Two or more of these bars 85

may be of thickened cross section to provide portions of sufficient thickness for the formation of openings 14 therein for the passage of the fastening screws or bolts 12 to secure the body section 2 and the plate 3 to the outlet box, as previously described. The plate or wall 3 is also provided with openings 14^a for passage of screws 12^a which enter threaded openings 14^b in the body plate 6 to hold the casing sections united to each other. The front or body plate or wall 6 is provided with a flattened rim portion 15 and an outwardly bulged, convex or dome portion 16 provided with a central circular opening 17 and annular concentric rows of 100 radially arranged elongated or oblong rectangular slots 18, the slots of the rows being disposed in staggered relation to each other. From the rim portion 15 projects a shallow annular flange 19 which lies in spaced relation to and parallel with the flange 9 of the back plate 3, thereby providing between said flanges an annular peripheral recess with which the slots 13 communicate.

105 The ventilated casing as thus constructed lies close to the wall or ceiling 5 and operates to ensure a quick and effective flow of heated air to and its circulation within the casing so as to obtain a rapid circuit closing action as hereinafter described.

110 The back plate 3 of the casing is provided with a pair of spaced longitudinal slots 20 separated by an intermediate intact portion or bridge piece 21. On the rear side of the 115 back plate is mounted an insulated carrier strip or support 22 for the switch proper and current carrying parts of the device. This carrier or support comprises an oblong rectangular block or strip of suitable electric insulating material. On the outer face of this strip 22 are mounted terminal plates 23 and 24 of phosphor bronze or other suitable material, and on the inner face of the strip is arranged a supporting block 25 arranged op- 120

posite the terminal plate 24. The terminal plate 23 is secured in position by screws 26 and 27, while the terminal plate 23 and the block 25 are secured in position by screws 28 and 29. The screws 27 and 28, the former of which passes through the strip 22 and the plate 23, and the latter of which passes through the strip 22, plate 24 and block 25, are provided with binding washers 30 and binding nuts 31.

The screw 26 has a conical or pointed inner end 32 projecting beyond the strip 22 and through one of the slots 20 into the casing chamber 33, said conical end of the screw providing a preliminarily adjustable but normally fixed circuit closing contact. Arranged within the casing for coaction with contact 32 is a movable switch member comprising a bimetallic strip 34 formed of two metals of different coefficients of expansion and contraction. These metal strip members are coextensive in length and welded together and are jointly secured at one end by the screws 28 and 29. This strip may be provided with a coating of a suitable material to protect the same from oxidation and corrosion, such, for example, as a coating of chromium. The screw 26 is provided with fine or micrometer screw threads, the threaded portion of said screw engaging threaded openings in the strip 22 and plate 23. Initially the outer end of the screw projects, as shown in Figs. 4 and 10, a suitable distance beyond the outer face of the plate 23 and is provided with a nick or other means whereby a screwdriver or other suitable tool may be engaged therewith to secure it in position. The screw body is preferably made of soft metal so that after having once been set or adjusted its outer end or projecting portion may be cut off flush with the outer face of the plate 23, as shown in Figs. 6 and 7, so as to prevent accidental displacement of said contact screw from its said position or meddlesome persons turning it and changing its position.

The pointed end 32 of the screw 26 lies in the path of movement of the free end of the strip 34, when the latter is bowed or deflected in one direction by the action of heat at a certain predetermined temperature, so that when the strip is thus bowed the free end of the strip will be brought into engagement with the pointed end of the screw for a circuit closing action.

The carrier or support 22 is adapted to be detachably secured in position to the back 3 by fastening screws 36 and 37. It will be observed that the switch proper and all the current carrying connections are thus mounted upon the common insulated support or carrier strip 22, which is detachably secured to the back 3, and which provides for the mounting of all the current carrying connections upon, or the dismounting of said current

carrying connections from, the back section of the casing in a simple and convenient manner, and so that when the parts are assembled all of the current carrying parts will be insulated from the casing and from the box 4. 70 It will also be seen that by this construction the switch contacts will be disposed at the front of the back 3 and in the casing chamber 33 while the binding posts project at the rear of the back 3 and into the box 4 for the ready connection of the circuit conductors A, A' therewith. In the device as organized for use the contact pin 26 lies within one of the slots 20, free from connection with the casing, while the block 25 projects through the other slot 20. In applying the unitary current carrying or switch structure to the casing body, said current carrying structure is brought into position on the exterior of the back 3 so that the free end of the strip 34 will be in alinement with the slot 20 to be occupied by the block 25, whereupon such end of the strip 34 is inserted through said slot and the current carrying unit then moved longitudinally in the direction toward the other slot 20 until the block 25 comes opposite the slot 20 through which the strip 34 has been introduced, after which the current carrying unit is simply moved inward to bring the parts thereof into working position and secured in place by means of the screws 36 and 37. When it is desired to remove the current carrying unit, all that is necessary is to unfasten the screws 36 and 37 and to shift the unit longitudinally in the reverse direction to that in which it was introduced and then to withdraw it laterally, as will be readily understood.

In accordance with my invention, the pointed contact portion 32 of the contact screw or member 26 is made of an alloy of gold and silver which will not oxidize or corrode under the action of corrosion inducing acids or gases of the character described. Also the strip 34 has its free end bent to form a contact portion 38 carrying a contact button or member 39 fitted and secured in an opening therein, which contact member or button may be made, like the point of the screw, of an alloy of gold and silver for the purpose described. The end 38 of the strip 34 is bent at an oblique angle thereto and at such an angle that in the movement of the strip toward the contact point 32 from the open position shown in Figs. 4 and 6 to the closed position shown in Fig. 7, the contact member 34 and its contact button 39 will be bowed, as shown in Fig. 7, and move in such an arc toward the contact point 32 that the distance between the fixed end of the strip and the contact 39 will be shortened so that a wiping action of part 32 on contact 39 will occur. Preferably this wiping action is increased by making the range of circuit closing motion of the end 38 of the strip 34 of a distance 130

greater than the distance normally between such end of the strip in its open position and the contact 32, so that the bowing of the strip will continue for a certain time after contact is made, with the result that the face of the button 39 will be drawn across the extremity of point 32 to obtain a strong rubbing or wiping contact. This rubbing or wiping contact will be of such character that, even in the event that there should be film or coating of an insulating material on the face of the button 39, said film or coating will be scratched off, so that there will be an absolute metal to metal contact between the parts 32 and 39 to ensure a certain and positive conducting engagement of the contacts and closing of the electric circuit.

The construction shown in Figs. 8, 9 and 10 is similar to that above described, except that the back rear wall or plate section 3^a of the casing 1^a is slightly modified in form to adapt it for cooperation with a standard surface outlet box 4^a, as employed in the surface mounting of the elements of an electrical alarm system including the supply conductors A and A', said back plate having a flattened rear face for abutting contact with the rim edge of the outlet box or a gasket interposed therebetween. The box may be suitably constructed for attachment to a ceiling or other wall surface or support carried thereby. This construction of the casing with back plate 3^a of small diameter and flat rear face is especially desirable for use in the application of the circuit closer to the surface mounted parts of a fire alarm system of a marine vessel. The box 4^a in this connection is here shown as adapted for attachment to the metallic ceiling 5^a of the vessel, and in this use of the circuit closer a sealing washer or gasket 4^b of rubber or other suitable waterproof and electric insulating material is preferably applied between the back 3^a and box 4^a to prevent leakage of water into the box, as well as to give protection against possible short circuiting of electric currents. The body section of the box in this construction is the same as that shown in Figs. 1, 2, 3 and 4.

In practice it is preferably intended to make all the body sections of the casing alike and interchangeable for use with back sections varying to certain degrees, as herein illustrated, for example, for application to different types of concealed and surface outlet boxes, so that changes in the back plates only will be necessary to adapt the circuit closer for use in conjunction with outlet boxes of all types. While the construction of box shown in Figs. 8, 9 and 10 is well adapted for marine service, as stated, it may also be used in all applications where a surface type of outlet box may be employed. The outlet box construction shown in Figs. 1, 2, 3 and 4 is adapted for use for flush mounting of the box

and cables or conduits in marine, industrial, domestic and commercial work of all kinds, as will be readily understood. In practice, it is preferred to bend the contact portion 38 of the strip 34 at an angle of about 45° to the strip, so as to secure a positive scraping contact with the contact point 32, as a result of which construction, and by making the contact members of an alloy of the character described, a type of temperature sensitive fire alarm switch employing a thermostatic contact strip is produced for efficient use in marine and commercial applications where corrosive influences have heretofore been an obstacle to the successful operation of contact making switches of this type.

By the provision of a casing of the construction described, material and important advantages are obtained. By casting or punching the casing of heavy sheet metal, preferably brass or bronze having corrosion resistance and providing a ventilated casing of this character full exposure of the temperature sensitive switch member 34 to heat waves entering the casing from all sides through the slots 13 or from the bottom or front through the slots 18 is allowed, thereby causing the strip to be quickly influenced and to close the circuit before the heat is absorbed by the relatively greater mass of metal in the base, while the casing at the same time offers a great mechanical protection to the heat sensitive element arranged therein. The purpose of making the slots or openings 13 and 18 of rectangular or oblong rectangular shape, instead of circular shape, is to secure a freer passage of heated air into and its circulation within the casing than can be obtained by the use of circular openings. This has been determined by test, as it is found that the tendency of air, water or other fluids passing through round holes is to cling to the edges of the holes and clog them, whereas sharp, straight-edged openings do not have this objection, and elongated straight-edged openings in particular, allow extremely free circulation of the air without clogging tendencies. Thus heated air rising in a room will be allowed to quickly enter the casing and displace the air contained therein, thus preventing banking or pocketing of air in the casing, which would interfere with the perfect and rapid closing of the circuit and sounding of the alarm. The purpose of providing the front wall of the casing with a bulged portion is to dispose the slots or openings 18 therein in such a manner as to catch and guide air coming in all directions into the casing. In this connection, also, the flanges 9 and 19 act as air deflectors or guiding surfaces to guide the air toward the slots or openings 13, while the surface 10 of plate 3 and corresponding surface of the outside of flange 9 of plate 3^a act as deflectors to ward off any moisture which may accumulate on

the ceiling and prevent the same from dropping or being conducted down into the casing chamber. The slots 18 in the bulged portion of the casing, furthermore, operate, when the casing is mounted in a pendant position, to allow any dust or other substances falling into the casing to discharge under the action of vibration or air currents.

From the foregoing description, taken in connection with the drawings, the construction and mode of operation of my improved circuit closing device will be readily understood and it will be seen that the invention provides a means for securing a positive engagement between the circuit closing contacts even under conditions where the contacts are coated with a film of dust, paint or other wall coating material, or are affected on the surface by oxidation or corrosion, so that all requirements in this connection may be effectually met for the provision of a circuit closing device which will be absolutely positive in action under the conditions mentioned. Also it will be seen that my invention provides a circuit closing device which may be employed in connection with an outlet box of any of the standard types and used in alarm or other circuits employing commercial line voltages.

Having thus fully described my invention, I claim:—

1. A temperature sensitive electrical circuit closer comprising front and rear walls and an intermediate wall, the front and intermediate walls having perforations therein, and a temperature sensitive circuit closing device carried by the rear wall and having circuit closing contacts disposed in advance of said wall and on the interior of the casing and having terminals for the connection of circuit conductors therewith disposed in rear of said rear wall.

2. A temperature sensitive electrical circuit closer comprising a casing having front and rear walls and an intermediate wall, said front and intermediate walls being provided with elongated rectangularly-shaped perforations therein, and a temperature sensitive electrical switch carried by the rear wall and having circuit closing contacts disposed within the casing and terminals for connection with electrical conductors disposed in rear of said rear wall.

3. A temperature sensitive electrical circuit closer comprising a casing having front and rear walls and an intermediate wall, said front wall being provided with annular series of radially arranged and staggered oblong rectangular openings, and said intermediate wall having an annular series of similarly shaped openings therein, and a temperature sensitive circuit closing switch carried by the rear wall and having circuit closing contacts disposed on the inner side of said rear wall within the casing and terminals for connection of electric conductors therewith disposed

on the outside of the casing and in rear of said rear wall.

4. A temperature sensitive electrical circuit closing device comprising front and rear walls and an intermediate wall of less diameter than said front and rear walls, said front wall and intermediate wall being provided with elongated openings therein, a temperature sensitive switch carried by the rear wall of the casing, and annular flanges on the casing at the front and rear of the intermediate wall.

5. In a temperature sensitive electrical circuit closer, an outlet box, a casing closing the open front of and detachably connected with said outlet box, said casing comprising front and rear walls detachably connected with each other and an intermediate wall carried by one of said walls, the front and intermediate walls being provided with air passages, and a temperature sensitive circuit closing device carried by the rear wall.

6. In a temperature sensitive electrical circuit closer, an outlet box, a casing closing the open front of and detachably connected with said outlet box, said casing comprising front and rear walls detachably connected with each other and an intermediate wall carried by one of said walls, the front and intermediate walls being provided with air passages, and a temperature sensitive circuit closing switch carried by the rear wall and having circuit closing contacts arranged in advance of said rear wall and within the casing and terminals for connection of circuit conductors therewith arranged in rear of the rear wall and within the outlet box.

7. A temperature sensitive circuit closer comprising a body section having perforate side and front walls, a back member having an outer face formed to close the open side of an outlet box and having an inner face formed to engage the said body section, and a switch carried by the back section and having terminals projecting at the rear of the back section so as to be disposed in the outlet box and having circuit closing contacts projecting at the front of the back section so as to be disposed in said body section.

8. A circuit closer of the character set forth in claim 7 wherein the switch device is of unitary type and detachably mounted on the back section.

9. A circuit closer of the character set forth in claim 7 wherein the body section comprises an annular body wall provided with elongated air openings and a front wall provided with similar openings.

10. A circuit closer of the character set forth in claim 1 wherein the front wall is provided with a domed portion in which the perforations thereof are formed.

11. A circuit closer of the character set forth in claim 7 wherein the body section comprises an annular body wall provided with

elongated air openings and a front wall provided with similar openings and with a rim flange.

12. A circuit closer of the character set forth in claim 1 wherein the front wall and the rear wall are formed with flanges arranged respectively in advance and in rear of the openings in the intermediate wall.

In testimony whereof I affix my signature.
